FIREPLACE CART FOR CARRYING AND STORING FIREWOOD

Tyler McVey, North Hollywood, Calif.

Application June 23, 1958, Serial No. 51,474

Term of patent 14 years

(Cl. D14—3)

Fig. 1 is a perspective view of a fireplace cart for carrying and storing firewood, showing my new design;

Fig. 2 is a side elevation thereof;

Fig. 3 is a front elevation thereof; and

Fig. 4 is a rear elevation thereof.

I claim:

The ornamental design for a fireplace cart for carrying and storing firewood, as shown.
